UNITED STATES PATENT OFFICE.

RICHARD KITSON, OF LOWELL, MASSACHUSETTS, ASSIGNOR TO THE KITSON MACHINE COMPANY, OF SAME PLACE.

COTTON-OPENER.

SPECIFICATION forming part of Letters Patent No. 351,868, dated November 2, 1886.

Application filed April 7, 1884. Serial No. 136,933. (No model.)

To all whom it may concern:

Be it known that I, RICHARD KITSON, of Lowell, in the county of Middlesex and State of Massachusetts, have invented a certain new and useful Improvement in Cotton-Openers, 5 of which the following is a specification.

My improvement relates to machines for opening and cleaning cotton; and it consists in certain improvements and combinations in 10 such machines, substantially as hereinafter described and claimed.

In the drawings is shown the machine described and shown in the Letters Patent granted to me July 17, 1877, No. 193,094, to which my 15 present improvements are represented as being applied.

Figure 1 is a longitudinal vertical section of the machine for opening and cleaning cotton containing my improvements. Fig. 2 is a view 25 of the machine, partly in section, provided with a modification of my improvements shown in Fig. 1, as hereinafter described. Fig. 3 is a vertical section through a part of the gage-box provided with said modification.

25 A is the outer casing of the machine. A feed-apron, a , is mounted upon rollers a' , a'' , upon which the fiber is placed to be carried forward to the grasping-rollers b , b . The dividing-rollers c , c tear apart and separate the 30 fibers, which fall from them into the gage-box d , whence the cotton is carried forward by the rolls e , e , e to the beater B . From the latter it is borne on the current of air created by the beater striking the cotton from the nip of the 35 rolls e , e , through the cotton-trunk T , to the condensing screen-cylinders s , s . The fiber is deposited upon the latter in the usual manner, and is dropped by them into the gage-box d . A doffer, d' , aids in removing the cotton from 40 the screens s , s after it passes through between them. From the gage-box d the cotton is carried forward to a second beater, B' , by the feed-apron e' and rolls e' , e' .

45 The above-described mechanism is well known, and is substantially, except doffer d' , shown in my patent above referred to and my Patent No. 222,410, granted December 9, 1879.

The doffer d' is driven by a pulley on the end 50 of its shaft outside the casing A , which is belted to any suitable counter-shaft, and said

doffer may be revolved in either direction and at any desired speed.

It frequently becomes necessary in the use of the machine to stop the grasping-rolls b , b , dividing-rolls c , c , and rolls e , e , e , e , and apron e' . When such is the case, the beater B and screens running in the usual manner, and with the machine constructed with a gage-box, d' , of the requisite size to furnish the sheet of cotton of proper thickness to the apron e' and rolls e , e , the cotton in the trunk T and upon the screens s , s continues to be deposited in the gage-box d' , while none passes therefrom. This gage-box thus frequently becomes filled entirely up to the screens s , s , and the latter 65 become clogged on account of it with the surplus cotton. To avoid this difficulty and at the same time feed forward a sheet of fiber of proper dimensions to the beater B' , I make my gage-box d' of double the width usually 70 employed in relation to the thickness of the sheet of fiber desired to be delivered by feed-rolls e , e longitudinally of the machine, as shown in the drawings, and suspend a swinging partition, p , Fig. 1, upon a pivot or rod, p' , 75 passing through the side walls of the gage-box on either side. This partition extends nearly across the inside breadth of the gage-box transversely of the machine and swings freely upon the pivot or rod p' . When the cotton falls 80 from the screens s , s into the gage-box d' , it drops first on one side of the partition p and fills the box on that side to the top of the partition. This presses over the lower end of the partition p toward the other side of the box. As 85 soon as the cotton has filled the space between one side of the box and the partition p up to the top of the latter, it falls on the other side of the partition p and fills the space on the other side of it. The gage-box d' thus receives 90 all the cotton in the trunk and on the screens s , s without difficulty or clogging of the screens. When the apron e' and rolls e , e are again set in motion, the cotton on the side of the partition p first filled in will be first fed forward to 95 the beater B' in a sheet of proper dimensions, because the lower end of the partition p was swung toward the other side of the box by the cotton on such side first filled. This is because the cotton on that side fills the space between 100

the partition p and its side of the gage-box in the form of a wedge, with the widest end of such body of cotton downward, and consequently slips downward easily. The cotton on the 5 side last filled will for the same reason, and because it is between the partition and its side of the gage-box with the smaller end downward, be held back until substantially all on the other side has passed forward to beater B^2 . 10 Then the cotton on the side last filled in, as described, will be released by the dropping back of the partition p to a perpendicular position, or nearly so, and will in turn pass forward to the beater B^2 . I thus double the holding capacity 15 of the gage-box d' in proportion to the thickness of the sheet delivered, while preserving its capacity to feed the cotton forward in a sheet of the proper dimensions.

Fig. 2 shows a modification of my improvement. The swinging partition p is made shorter, and the pivot p' , on which it swings, is placed lower down in the gage-box, and one end of it projects through the side of the gage-box, and has attached to it on the outside of 20 the box an arm, m , on the end of which is a weight, m' . Pins m^2 m^2 are driven into the outside of the gage-box to arrest and hold the arm m when it and the weight are thrown over either way by hand, which pins project far 25 enough from the side of the gage-box to be in the path of the arm. Above the swinging partition p is placed, within the gage box and crossing the same in line with the axis p' , the supplemental vertical fixed partition p^2 , extending entirely across the gage-box from side to side. The pins m^2 m^2 are placed in such relation to the arm m and swinging partition p 30 that when the arm is arrested by one of them the swinging partition will be inclined under 35 the cotton on one side of the fixed partition 40

p^2 and prevent its falling downward upon the apron e^2 and rolls e^3 e^3 , and when the arm m is thrown over the other way and arrested by the other pin m^2 the swinging partition will in like manner prevent the cotton passing downward below the other side of the fixed partition p^2 . 45

I do not confine the use of my improvement to a machine in which the screens s are used or in which the precise form of the apron e^2 and rollers e^3 e^3 is used, as it is evident that the screens may be omitted and other forms of drums or rollers may be used to convey the cotton out of the gage-box d' . 50

What I claim as new and of my invention is— 55

1. In combination with the gage-box d' , the swinging partition p , adapted to obstruct either division of the gage-box and prevent passage of fiber therein, substantially as described. 60

2. The combination of the cotton-trunk T , screens s , the gage-box d' , and the swinging partition p , substantially as described.

3. The combination of the gage-box d' , swinging partition p , apron e^2 , and rolls e^3 e^3 , 65 substantially as described.

4. The combination of the trunk T , the gage-box d' , and the swinging partition p , substantially as described.

5. The combination of the gage-box d' , the swinging partition p , adapted to obstruct either division of the gage-box and prevent the passage of fiber therein, and the arm m , connected to the axis of the partition on the outside of the gage box and adapted to move the partition, substantially as described. 75

RICHARD KITSON.
